UNITED STATES PATENT OFFICE.

MATTHEW C. O'CONNOR, OF NEW HAVEN, CONNECTICUT.

FIRE-ESCAPE.

SPECIFICATION forming part of Letters Patent No. 297,710, dated April 29, 1884.

Application filed May 23, 1883. (No model.)

To all whom it may concern:

Be it known that I, MATTHEW C. O'CONNOR, a citizen of the United States, residing at New Haven, in the county of New Haven and State 5 of Connecticut, have invented certain new and useful Improvements in Fire-Escapes, of which the following is a specification, reference being had therein to the accompanying drawings.

This invention relates to portable fire-escapes; and it consists in certain improvements 10 in the construction thereof, whereby the same can be readily operated and controlled by the party using the same, and also be readily carried from place to place by hand, and be 15 stowed away, when desired, in a very small compass, as will be hereinafter described and claimed.

In the drawings, Figure 1 represents a side elevation of the escape in readiness for use. 20 Fig. 2 represents a sectional side elevation of the case and parts inclosed thereby.

A represents the case, which is of any suitable or desired form, such as round, square, octagonal, but preferably round, as shown in 25 the drawings. Centrally of this case and through the same extends a spindle or shaft, B, which at one end is journaled in the fixed back plate, C, its other end passing through a removable front plate, D, which is secured 30 in position by means of screw-bolts E, which pass through the case and are held by nuts F. Upon the free end of the spindle or shaft B is mounted a hand-wheel, G.

H represents a webbing chain or rope, which 35 is secured at one end, by any suitable means, to the shaft B within the casing, and is coiled therearound, as shown in Fig. 2. As the hand-wheel is turned to the right, the shaft will be rotated, so as to coil the webbing chain or rope 40 H tightly around the same, while by turning the hand-wheel G in the reverse direction the coil will be loosened, so as to permit the material H to readily pay out.

From the upper part of the inner face of the 45 back plate, C, project inwardly a series of rounded bearing-pins, I J K L M, around which the webbing or other material H travels, and a pair of friction-blocks, N and O, across one face and end of one of which and between both 50 of which said webbing passes.

To the outer end of the webbing H is at-

tached a ring or hook, P, by means of which the apparatus is attached to a window-sill or other suitable part of a building, article of furniture, or other anchorage. That part of 55 the webbing just below the hook or ring P is incased in leather, a', as shown, to prevent the friction of the webbing against the window-sill fraying said webbing.

Q represents a sling of webbing or other suitable material, connected either directly to the case A, or removably attached thereto or to straps R, depending from ears S thereon, by a ring and snap-hook, as shown, or in any other suitable manner. It is preferred that said sling 60 be removably attached, substantially in the manner shown, as thereby a person desiring to use the escape can more readily place said sling around his body and fasten it in position than would be the case were the sling unprovided 65 with means for connecting and disconnecting the same from the case A.

The hook or ring P having been properly anchored, and the sling adjusted in position around the party contemplating using the escape, the user with one hand grasps the leather-covered strap T, and with the other hand turns the hand-wheel from left to right. This action will have the effect of loosening the webbing or other material, H, coiled around the spindle 75 or shaft B, whereupon the weight of the person in the sling will drag down the case A, and consequently cause the webbing H to pay out from the case A. As the webbing or other material, H, uncoils, it first passes over and 80 across the top of the rounded pin I, thence horizontally to and across the under face of the pin J, and from thence upward to and over the pin K. It then passes in an angularly downward direction to and horizontally across 85 the rounded lower ends of the clamp or brake N O, and from thence in an upward angular direction to and across the outer face of the pin L, to and around the pin M, from whence it passes vertically downward across the outer 90 face of the friction-block O of the clamp or brake, and around the rounded lower end thereof to and up between the friction-blocks N O. It will thus be seen that as the webbing or other material, H, pays out it is guided 95 around the pins I J K, the weight of the user pulling down the case creating a tension on 100

the webbing that insures the same being held in frictional contact with the respective pins during its passage over the same. From pin K the webbing passes down vertically to and 5 horizontally across the rounded lower ends of the friction-blocks N O up to and around the pins L M on the opposite side, and from thence down the outside and around the rounded bottom end of the friction-block O, and up 10 between the blocks N O. It will be seen from this that while a portion of the webbing is passing in a horizontal direction across the lower ends of the friction-blocks another portion of said webbing is traveling in a vertical 15 direction, and that at the lower end of friction-block O the webbing passes in opposite horizontal directions and in frictional contact. By this means the frictional contact of the webbing with the several parts above enumerated 20 and with a portion of itself results in securing an automatic braking of the webbing while in use. The user having placed the sling in position around his body, (or, if desired, such sling may be of sufficient width to permit of 25 the person seating himself therein,) he grasps the strap R with one hand, and with the other turns the hand-wheel, so as to loosen the coil of webbing within the case. When the coil is loosened, the weight of the person in the sling 30 will operate to draw down the case, and as the upper end of the webbing is rigidly secured

by means of the hook or ring to some suitable anchorage, it will necessarily follow that the webbing will pay out as the case descends.

Having thus described my invention, what 35 I claim therein is—

1. In a portable fire-escape, the combination of the case A, having rounded bearing-pins I J K L M projecting from the inner face of the back plate, C, and friction-blocks N O, arranged between said bearing-pins, webbing or other suitable material, H, means, substantially as described, for coiling and uncoiling the same, and the sling Q, substantially as and for the purpose set forth. 40

2. The fire-escape herein described, consisting of case A, having rounded bearing-pins I J K L M, and friction-blocks N O, having rounded lower ends, webbing or other suitable material, H, adapted to travel across 50 the faces of said pins, and across the rounded lower ends of both of and around one and between both of said friction-blocks, central shaft, B, hand-wheel G, and sling Q, substantially as and for the purpose set forth. 55

In testimony whereof I affix my signature in presence of two witnesses.

MATTHEW C. O'CONNOR.

Witnesses:

JOHN A. PECKHAM,
W. HITCHCOCK.
